The ornamental design for a package as shown and described.

DESCRIPTION

FIG. 1 is a front view of a first embodiment of a package showing our new design;

FIG. 2 is a rear view of FIG. 1;

FIG. 3 is a front view of a second embodiment of a package showing our new design; and,

FIG. 4 is a rear view of FIG. 3.

A perspective view, a top view, a bottom view, a right side view, and a left side view of the package have been omitted because the package is thin and flat and no additional ornamental details would be visible in these views.
